CLAIM

The ornamental design for a furniture for marine vessel, as shown and described.

DESCRIPTION

FIG. 1 is a side perspective view from the front of a first embodiment of furniture for a marine vessel according to our new design;

FIG. 2 is a side perspective view from the back thereof; FIG. 3 is a top perspective view from the side thereof;

FIG. 4 is a top plan view thereof;

FIG. 5 is a side elevation view thereof;

FIG. 6 is a side perspective view from the front of a second embodiment of furniture for a marine vessel according to our new design, which is a mirror image of the first embodiment;

FIG. 7 is a side perspective view from the back thereof;

FIG. 8 is top perspective view from the side thereof;

FIG. 9 is a top plan view thereof; and,

FIG. 10 is a side elevation view thereof.

The broken lines in the figures illustrate portions of the furniture for a marine vessel that form no part of the claimed design.

1 Claim, 8 Drawing Sheets
